(57) **CLAIM**

The ornamental design for a case for a mobile electronic device, as shown and described.

DESCRIPTION

FIG. 1 is a top-front perspective view of a design for a case for a mobile electronic device in a closed configuration;

FIG. 2 is a bottom-rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof;

FIG. 8 is a bottom view thereof;

FIG. 9 is a top-front perspective view of the design for a case for a mobile electronic device in an open configuration;

FIG. 10 is a bottom-rear perspective view thereof;

FIG. 11 is a front view thereof;

FIG. 12 is a rear view thereof;

FIG. 13 is a left-side view thereof;

FIG. 14 is a right-side view thereof;

FIG. 15 is a top view thereof; and,

FIG. 16 is a bottom view thereof.

The broken line portions in the drawings are shown to illustrate environment only and form no part of the claimed design.
